APPARATUS FOR COOLING CONTAINERS

Walter C. Hilger, Chicago, Ill., assignor of one-half to Herbert Scheurer, Chicago, Ill.

Refiled for abandoned application Serial No. 20,723, May 10, 1935. This application December 4, 1937, Serial No. 178,063

16 Claims.

(Cl. 62—1)

This application has been refiled for my abandoned application Serial Number 20,723, filed May 10, 1935.

It contemplates more especially the provision of efficacious means and improved application of a cooling medium to temper containers preparatory to the filling thereof.

The teachings of my invention, although not limited to such use, is particularly adapted to 10 the bottling of milk and similar substances that require carefully regulated temperatures to prevent the undesirable multiplication of the bacteria normally present in raw or pasteurized milk. Then, too, edible substances like milk are 15 refrigerated immediately after pasteurization is effected, and it is desirable to avoid any appreciable re-warming thereof during the filling process. Any increase in temperature should be avoided in order to maintain the maximum cream 20 volume and to economize on refrigeration.

Accordingly, the invention is purposed to provide improved bottling equipment with means for cooling the washed bottles in a manner to insure their presentation to the filling machine at the 25 proper temperature to effectually guard against any heat absorption by the contents from the bottles or containers that are presented for filling with normally unstable contents. The bottles or containers are cooled to a temperature 30 that is substantially commensurate with that of the liquid or other substance which has already been maintained under refrigeration to insure the proper preservation thereof.

One object of the present invention is to simplify the construction and improve the operation 35 of devices of the character mentioned.

Another object is to provide cooling apparatus that effectively cools containers preparatory to and without interrupting the continuity of filling 40 machine operations.

Still another object is to provide improved container cooling means that operate in accordance with the operating speed of the filling machine.

A further object is to provide a self-contained 45 bottle cooling apparatus that is readily interposable between the washing and filling machines of existing installations.

A still further object is to provide a bottle 50 cooling device adapted to pre-cool open bottles with any suitable cooling medium directed exteriorly thereover without entering the bottle interiors.

Still a further object is to provide an efficient 55 self-contained device for efficaciously pre-cooling

bottles without interfering with the continuity of bottle washing and filling operations.

An additional object is to provide a cooling device which is readily adjustable to pre-cool containers of different sizes.

An additional object is to provide a continuous improved method of pre-cooling containers without interrupting or curtailing the continuity of container washing and filling.

Other objects and advantages of the invention 10 will appear from the following description of an illustrated embodiment of the present invention.

In the drawings:

Figure 1 is a side view in elevation of a bottling plant installation showing bottle washing, cooling 15 and filling units and associated conveyer equipment to enable a continuity of operations without interruption.

Figure 2 is a perspective view of the bottle cooling unit embodying features of the present 20 invention.

Figure 3 is a sectional view in elevation taken longitudinally through the bottle cooling unit shown in Figure 2.

Figure 4 is a transverse sectional view in elevation taken substantially along line IV—IV of 25 Figure 3.

Figure 5 is a sectional view in elevation taken substantially along line V—V of Figure 3.

The structure selected for illustration is shown 30 in connection with the bottling of milk which requires that the bottles be filled at temperatures substantially below the normal room temperature. It will be obvious, however, that the invention may be used with equal advantage for 35 other purposes and in packaging of other container filled substances to present bottles or containers for filling, at any desired temperature, either below or above the normal room temperature.

The preferred embodiment illustrates a method 40 and apparatus for cooling containers, there being shown a bottle washing unit 5 of any conventional construction which delivers containers to a cooling unit 6 for presentation to a filling 45 unit 7. Suitable conveyer equipment 8 for carrying the bottles from the washing unit to the cooling unit, is provided to insure a continuity of operations without resort to manual effort. The washing and filling units 5 and 7 may be of any 50 suitable or approved construction to perform their respective functions automatically and in interdependent relation with a cooling unit embodying features of the present invention. The conveyor 8 may also be of conventional construc- 55

tion and, in this instance, comprises an endless belt conveyor driven by any suitable driving mechanism of standard construction (not shown).

5 For efficient and universally adaptable operation, the operating speeds of the units and the conveyor are variable and capable of being coordinated so that the washing unit 5 will supply washed bottles and the conveyor 8 will carry 10 these bottles to the cooling unit 6 in a predetermined speed and continuity of operation determined in accordance with the requirements of the filling unit 7 so that the latter may operate uninterruptedly at the most efficient speed to 15 produce the maximum capacity.

The cooling unit 6 is interposed between the washing unit 5 and the filling unit 7, it being preferably located immediately adjacent the filling unit 7 so as to deliver the cooled bottles directly 20 to the latter without any appreciable time interval. As shown, the washed bottles are delivered from the washing unit 5 by the conveyor 8 to the cooling unit 6 which pre-cools the bottles to the desired temperature while in movement 25 toward the filling unit 7 at any predetermined rate of movement. The cooling unit 6 then delivers the cooled bottles directly to the filling unit 7. In the event that the latter unit is shut down temporarily or its operation is interrupted or delayed for any reason, the bottles 30 in the cooling unit 6 are retained therein and are maintained at the proper temperature until full coordinated operations are resumed by all the units to insure a continuity of operations. 35 Thus, there will be no opportunity for the bottles to become warm during the shut-down period, and proper temperature at the time of filling is thereby maintained.

The cooling unit 6 embodies a novel combination 40 and arrangement of parts to efficiently cool containers or bottles as they are conveyed to the filling unit 7 at a predetermined rate of movement. As shown, the cooling unit 6, in this instance, comprises a substantially rectangular, 45 elongated base or casing 9 defining an interior chamber to support the various structural parts that are essentially enclosed in the casing 9. The confines of the casing 9 defines a cooling zone of sufficient length to insure the proper cooling of 50 bottles as they pass through at a predetermined rate. The casing 9 may be constructed of sheet metal or other suitable material with the sides thereof preferably comprising hinged panels 10 to provide convenient access to the interior 55 thereof.

For conveying the bottles through the cooling zone of the unit and for insuring their proper cooling, a flexible endless inter-linked chain conveyor 11 is provided to extend substantially for 60 the length of the casing 9 to insure that the bottles will be sufficiently exposed to the cooling medium to attain the desired temperature drop while moving through the unit 6. The endless conveyor 11 is of compact construction, it being 65 particularly advantageous to pass the least amount of conveyor body through the cooling zone of the unit for decreasing or minimizing refrigerating losses.

The cooling of the containers in continuity and 70 timed sequence with the washing and filling operations renders possible the unitary and self-contained construction of the cooling apparatus which adapts it for convenient installation in existing bottling plants without entailing any appreciable labor, time or expense. The individual 75

conveyor 11 for the unit 10 preferably comprises a flexible endless belt or chain 11 preferably though not essentially comprising interconnected links (Figures 3, 4 and 5) supported for movement longitudinally of the casing 9 by sprockets 12 disposed in a horizontal plane at opposite ends of the casing. The sprockets 12 are rotatively mounted on shafts 13 disposed transversely of the casing for journaled support in brackets 14 projecting inwardly from and attached to the end walls of the casing 9. The brackets 14 so locate the sprockets 12 that the upper run of the conveyor belt or chain 11 is at substantially the level of the filling table of the unit 7 at one end, and in the same plane as the conveyor 8 at the other end. 15

Any suitable means may be provided for driving the conveyor in coordinated timed relation with the conveyor 8 supplying bottles or other containers from the washing unit 5. In the present 20 embodiment, the driving instrumentalities consist of a chain-and-sprocket driving connection between the conveyor 11 and the conveyor 8. To this end, a sprocket 15 is fixed to the shaft 13 which carries the conveyor supporting sprocket 25 12 at the receiving end of the cooling unit 6 (Figure 4). A flexible drive chain 16 (Figures 1 and 4) meshes with the toothed periphery of the sprocket 15 to extend over and mesh with the periphery of a similar sprocket 17 carried by the 30 shaft which supports the discharge end of the conveyor 8 leading from the washing unit 5. Consequently, the cooling unit conveyor 11 is driven in timed relation with the washing unit conveyor 8, and the bottles or containers are 35 efficiently carried from the washing unit 5, through the cooling unit 6, and delivered to the filling unit 7 as will appear more fully hereinafter.

The bottles or containers are transferred from the washing unit conveyor 8 to the cooling unit 40 conveyor 11, and from the cooling unit conveyor 11 to the filling unit 7 with the aid of suitable platforms 18 provided at both ends of the cooling unit 6. The platforms 18 consist, in this instance, of flat metallic plates secured to the cooling unit casing 9 with their upper surfaces horizontally aligned with the upper run of the cooling unit conveyor 11. The ends of the plates 18 may be suitably shaped to permit them to be fitted closely to the cooling unit conveyor 11 45 without actually touching it so that the bottles or containers may slide easily from the cooling unit conveyor 11 to the plates 18 or vice versa. After being deposited on one of the plates 18, a bottle will be pushed along by the next following 50 bottle so that they will be discharged in a continuous series when the washing, cooling and filling equipment is in operation.

To guide the bottles as they are being conveyed through the cooling unit 6 by the conveyor 11, 60 and to align them in a row suitably spaced with respect to the cooling instrumentalities, a pair of spaced guide members 19 are provided in operative relation with the cooling unit conveyor 11. The guide members 19 comprise, in this instance, 65 a confronting pair of guide bars 19 disposed adjacent and above the opposite sides of the cooling unit conveyor 11 to extend longitudinally thereof for the entire length of the cooling unit casing 9. The guide bars 19 are preferably supported at opposite ends by bracket arms 20 which hold them in a position to define a predetermined passageway along which the bottles may be carried by the cooling unit conveyor 11. The extremities of the guide bars 19 are preferably 70 75

flared outwardly (Figure 2) so that the bottles may be gradually moved into alignment as they are advanced to the cooling unit conveyor 11 from the washing unit discharge conveyor 8.

5 In order to provide for the handling of bottles of different diameters, the guide bars 19 are preferably mounted for adjustment to vary their relative spacing to accommodate differently sized and styled bottles or containers. To this end, the 10 guide bar supporting bracket arms 20 are provided on their lower ends with comparatively shorter horizontally projecting arms 20'. Supporting and operating links 21 are pivotally connected to both ends of each of the link arms 20'. 15 The links 21 are, in turn, pivotally connected at their opposite extremities to end walls of the cooling unit. The guide supporting brackets 20 are provided, therefore, with a rocking back and forth movement or adjustment while retaining the parallel relationship between the oppositely disposed 20 guide bars 19.

As a means of adjusting and remotely controlling the position of the guide bars 19 and their instrumentalities for positioning the guide bars 25 19, the innermost pair of links 21 are of the bell crank lever type having their shorter arms 21' projecting toward and crossing each other. The shorter bell crank arms 21' are, in turn, pivotally connected to the extremities of links 22 intersecting for pivotal connection with the free extremity of an actuator lever 23 fixed to a shaft 24 suitably journaled at opposite ends in the end walls of the cooling unit casing 9. One lever 23 is provided at each end of the cooling unit casing 9 for 30 operative connection to the brackets 20 carrying the guide bars 19 which can be shifted in unison by the rocking of the shaft 24 which projects through the end walls of the casing 9 to render such externally accessible. Rocking of the shaft 40 24 may be conveniently effected by means of an externally accessible manual lever 25 secured to the outer end of the shafts 24. The manual levers 25 are preferably located externally of the base 9 so as to be easily accessible. In order that the 45 guide bars 19 may be retained in any desired position, locking means of suitable character such as a toothed segment 26 and spring operated pawl latch 26', may be operatively associated with the manual operating member 25. Accordingly, the 50 guide bars 19 may be set to a desired position and locked securely in any predetermined spaced relation for guiding bottles or containers of any particular size, shape and type.

As the bottles are being conveyed through the 55 cooling unit 6 by the conveyor 11, they are cooled to the desired temperature in a manner to be presently described. The cooling is effected, in this instance, by spraying or otherwise directing a suitable fluid or refrigerant carrying medium 60 such as cold water of the proper temperature. The water may be directed over or preferably against the exterior of a number of bottles simultaneously by any suitable means such as spray nozzles 27 positioned above and on each side of 65 the cooling unit conveyor 11 so as to direct the water downwardly over or against the side of the bottles. As shown herein, the spray nozzles 27 comprise pipes or tubes of substantially the same length as the conveyor 11 and disposed parallel 70 to and above the conveyor. The pipes 27 are provided with suitably spaced apertures for directing the water downwardly and toward the bottles on the conveyor 11.

Support for the nozzles 27 is provided by a hood 75 structure carried by the casing 9 and spaced sub-

stantially above the conveyor 11. The hood structure includes, in this instance, brackets 27' at each end, the brackets 27' being formed with downwardly projecting ears to which the respective nozzle tubes may be secured at their opposite ends. The brackets 27' also provide support for a cover member 28 and a pair of guard members or shields 29 preferably of hard rubber material which serve to preclude the entrance of cooling fluid or other material to the interior of 10 the bottles. As shown herein, the cover member 28 comprises a shallow, generally U-shaped trough of sheet metal or other suitable material, carried in an inverted position above the conveyor 11. The side portions of the trough 28 are 15 formed of sufficient length to project well beyond the sides of the conveyor 11 to provide ample protection for the open mouths of the bottles.

The guard members or shields 29 preferably comprise relatively long, narrow rectangular strips 20 of hard rubber that are preferably supported along one edge for pivotal movement on axes parallel to the longitudinal axis of the conveyor. The hard rubber shields 29 are capable of yielding during their edge engagement with the bottle 25 necks to effectively serve their purpose. In the present instance, pivotal support is provided by shafts 30 journaled at opposite ends in suitable bearings formed in the brackets 27'. Each shaft 30 is flattened along one side to provide a convenient means for attaching thereto the bottle mouth shields 29. With the shields 29 mounted in this manner, their lower edges are disposed parallel to each other and project downwardly below the mouths of the bottles on the conveyor 11. 35 The pivotal mounting of the shields 29 permits their displacement so that their free edges engage the bottle necks and thus serve to direct the fluid delivered by the nozzles 26 against the shields 29 to drop downwardly along the sides of the bottles 40 and away from the open mouths thereof.

Engagement of the shields 29 with the bottles is insured by counterbalanced arms 31 secured to the shafts 30 in a manner such as to rotatively urge the shafts 30 and shields 29 toward each 45 other in engagement with the bottle necks. The open bottles are, therefore, effectually protected against the entrance of cooling fluid or other material, and the bottles are discharged by the conveyor 11 in proper condition to the filling unit 1. 50 It will be apparent from the foregoing that the interior of the bottles or containers previously washed and rendered sterile by the unit 5, will not be contaminated by the cooling medium which is directed against the shields 29 and the exterior 55 walls of the bottles or containers. The cooling medium drops from the shields 29 on to the bottle exteriors without any possible entrance into their interiors.

In order to enable the cooling medium and 60 shields 29 to function properly with bottles of different heights, the hood 28 and associated equipment supported therewith, is mounted for adjustment vertically with respect to the cooling unit casing 9 and conveyor 11. To this end, the 65 brackets 27 are formed with outwardly projecting arms 32 having recessed extremities to receive and engage vertical supporting rods 33 provided proximate to the four corners of the casing 9. The rods 33 are guided for vertical movement in 70 bearings 34 carried by the end walls of the casing 9, they being supported at the extremities of transverse support bars 35 disposed within the casing 9. The bars 35 are, in turn, supported intermediate their ends by a vertically disposed rod 75

36 which is slidably mounted for vertical movement in a bearing 37 fixed to each end wall of the casing 9. For raising and lowering the hood 28 and its associated structure, a lever 38 is fixed to a shaft 39 which is journalled in suitable bearings mounted in the end walls of the casing 9. An actuating lever 38 is provided proximate to each end of the casing 9 and each has its outer end 10 operatively connected through toggle links 38' to the vertical supporting rod 36 which effects and guides the vertical displacement of the cross-bars 35 which support the rods 33 and the hood 28 superposed thereon with auxiliary instrumentalities. The shaft 39 projects through the end walls of the casing 9, to receive a manually operable member or lever 40 rigidly secured thereto and disposed externally of the casing 9 for convenient access. The displacement of the lever 20 40 in a clockwise direction (viewed from Figure 4) will serve to elevate the hood 28 and its supporting structure and hood together with the cooling and shielding apparatus relative to the conveyor 11. Shifting the lever 40 in a counterclockwise 25 direction (viewed from Figure 4) lowers the hood 28 and other apparatus associated therewith. In order to lock the levers 40 in any desired position, they are provided with suitable locking means comprising, in this instance, a toothed segment 30 41 and spring pawl latch mechanism 41' carried by the lever 40 similarly to the levers 25 described supra. The hood 28, shields 29, and associated parts may be vertically adjusted to function effectively with bottles of different heights while 35 the conveyor guides 19 are horizontally adjustable to accommodate bottles or containers of different diameters or widths.

A suitable refrigerant or refrigerating medium such as cold water for cooling the bottles, is 40 delivered to the spray nozzles 26 through a system of ducts by means of a pump 42 driven by an electric motor 42'. Since the adjustment of the spraying and associated apparatus will result in position variations in the distance between 45 such apparatus and the pump 42, the duct system is of a flexible character to properly function under these conditions. To this end, the pump 42 is arranged to discharge into a rigid conduit 43 extending vertically along the side 50 of the casing 9 and terminating at a point slightly above its upper edge. A T-union 44 fitted to the upper end of the conduit 43, provides for a fluid supply to the two spray nozzles 26. In this instance, the fluid supply from the conduit 43, 55 is connected to the spray nozzles 26 by means of flexible tubes 45 which communicate between the T-union 44 and suitable inlet nipples formed on the respective nozzles 26. The flexible character of the tubes 45 permits the cooling apparatus to be raised or lowered as desired, without 60 interfering in any way with the supply of cooling fluid.

As a means for maintaining the cooling fluid at the proper temperature and permitting its 65 repeated use by recirculation, the cooling unit 6 may be provided with refrigerating apparatus conveniently disposed within the hollow casing 9 or externally thereof depending upon the dictates of commercial practice or the requirements 70 of any particular installation. The refrigerating apparatus includes, in this instance, a pipe coil unit 46 of standard or approved construction through which a suitable refrigerant may be circulated by a refrigerant unit (not shown) of any 75 suitable type ordinarily provided for this purpose.

As shown, the refrigerant is delivered to the coil 46 through an inlet pipe 47 and returned to the refrigerant unit (not shown) through an outlet pipe 48. A suitable surge tank 49 of well known construction may desirably be interposed in the 5 refrigerant circulating system to increase the efficiency of the apparatus.

The refrigerant coil 46 is preferably disposed in an edgewise position so that its parallel pipe sections are vertically superposed below the conveyor and substantially parallel thereto. Suitable brackets 50 are attached to the casing 9 and serve to hold the coil 46 in place. The cooling fluid after passing over the bottles on the conveyor 11, is collected in a substantially V-shaped 15 trough 51 mounted in the upper part of the casing 9 between the conveyor 11 and the coil 46 so as to direct the water downwardly over the coil 46 for further cooling and recirculation as will appear more fully hereinafter. To this end, 20 the trough 51 is provided with a narrow outlet extending substantially throughout its length and disposed immediately above the uppermost pipe section of the coil 46. The fluid collected in the trough 51 is thus directed over the upper part of 25 the coil 46 and in its downward path is deflected over the lower sections of the coil 46 by means of inclined deflecting vanes or baffles 52 disposed intermediate the pipe sections and superposed adjacent the sides of the coil 46.

The fluid is thus brought into contact with the cold pipe surfaces of the refrigerating coil 46 and is cooled to the proper temperature before being deposited in the bottom of the casing 9 for re-circulation. The cold fluid is preferably 35 collected and confined in a reservoir or tank 53 formed in the bottom of the casing 9 for re-circulation. To this end, the pump 42 withdraws the cooled fluid from the casing bottom or tank 53 and delivers such under pressure to the spray 40 nozzles 26 described supra. To insure the maintenance of this fluid at the proper temperature, the tank 53 comprises spaced walls defining a 45 compartment with insulating material 54 of any suitable character to minimize thermal conduction and reduce the cold loss to a minimum.

In operation, the washed bottles will be delivered by the washing unit 5 over the conveyor 8 to the cooling unit 6 at a suitable rate determined by the operating speed of the filling unit 7. The cooling unit 6 having been suitably adjusted in accordance with the size of the bottles to be filled, will receive the bottles from the conveyor 8, cool them to the desired temperature, and deposit them on the filling table of the filling 55 unit 7. The filling unit 7 may be stopped momentarily, if necessary, without necessitating any interruption in operation of the cooling unit 6. During the inoperation of the filling unit 7, the bottles awaiting filling will be retained in the 60 cooling unit and kept at or until the selected temperature has been acquired by the bottles. This is a factor of the travel speed of the conveyor 11, its length or capacity of the cooling unit 6, and the desirability of continuously or intermittently operating the conveyor 11. All these factors are capable of variations depending upon the dictates of commercial practice and the requirements of any particular installation.

Upon the filling unit 7 resuming operation, the 70 bottles will again be presented thereto by the conveyor 11 at the desired low temperature. In view of the foregoing, it will be apparent that an improved arrangement and organization of bottling equipment has been provided particularly 75

though not exclusively suitable for the bottling of milk. The bottles are presented for filling in a clean and sanitary condition and at exactly the correct temperature for best results. Cooling is effected while the bottles are in movement toward the filling unit, the apparatus being so designed and constructed as to insure their exposure to the cooling medium a sufficient time to reduce their body to the proper temperature.

10 Moreover, the cooling apparatus is of improved construction and self-contained to permit its ready use with existing container washing and filling installations. The cooling apparatus is efficient and reliable in operation, relatively simple 15 and inexpensive to manufacture, and is well adapted to perform its intended functions, that is very efficaciously accomplished from a production standpoint when interposed between washing and filling units in synchronized timed 20 relation therewith.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

30 1. In a device of the character described, the combination with means for feeding containers along a predetermined path, of spray means in said path to direct a cooling medium against the containers for lowering the temperature of the 35 containers to a selected degree, a hood over said spray means along said feeding means, spray deflector means depending from said hood, and means in said path for directing the discharge of the cooled containers to a predetermined position.

40 2. In a device of the character described, the combination with means for feeding containers along a predetermined path, of spray means in said path to direct a cooling medium against the containers for lowering the temperature of the 45 containers to a selected degree, means for angularly adjusting said spray means, and means in said path for directing the discharge of the cooled containers to a predetermined position.

3. In a device of the character described, the 50 combination with means for feeding containers along a predetermined path, of spray means in said path to direct a cooling medium against the containers for lowering the temperature of the containers to a selected degree, means for adjusting said spray means, and deflector means associated with said spray means for precluding the cooling medium from said spray means to enter the interior of the containers.

4. In a device of the character described, the 60 combination with means for feeding containers along a predetermined path, of spray means in said path to direct a cooling medium against the containers for lowering the temperature of the containers to a selected degree, means for adjusting said spray means, and deflector means pivotally mounted to engage the containers below the mouth thereof for precluding the cooling medium from said spray means to enter the interior of the containers.

70 5. In a device of the character described, the combination with means for feeding containers along a predetermined path, of spray means in said path to direct a cooling medium against the containers for lowering the temperature of the 75 containers to a selected degree, means for ad-

justing said spray means, deflector means pivotally mounted to engage the containers below the mouth thereof, and means for normally urging said deflector means in container engaging position for precluding the cooling medium from 5 said spray means to enter the interior of the containers.

6. In a device of the character described, the combination with means for feeding containers along a predetermined path, of spray means in 10 said path to direct a cooling medium against the containers for lowering the temperature of the containers to a selected degree, means for adjusting said spray means, deflector means pivotally mounted to engage the containers below the 15 mouth thereof, means for normally urging said deflector means in container engaging position for precluding the cooling medium from said spray means to enter the interior of the containers, and means for recirculating the cooling means 20 for discharge through said spray means.

7. In a device of the character described, the combination with a frame, of means on said frame for feeding containers along a predetermined path, container cooling means along said path, 25 adjustable means for guiding containers along said path, and means for adjusting said container cooling means to the requirements of differently sized containers.

8. In a device of the character described, the 30 combination with a frame, of a casing mounted on said frame, means on said frame for feeding containers along a predetermined path, container cooling means in said path, adjustable means for guiding containers along said path, means for 35 adjusting said container cooling means to the requirements of differently sized containers, and control means accessible externally of said casing to operate said adjustable container guide means.

9. In a device of the character described, the 40 combination with a frame, of a casing mounted on said frame, means on said frame for feeding containers along a predetermined path, container cooling spray means adjustably mounted in said path, adjustable means for guiding containers along said path, means for adjusting said 45 container cooling means to the requirements of differently sized containers, and control means accessible externally of said casing to operate said adjustable container guide means.

10. In a device of the character described, the combination with a frame, of a casing mounted on said frame, means on said frame for feeding containers along a predetermined path, container cooling spray means adjustably mounted in 50 said path, adjustable means for guiding containers along said path, means for adjusting said container cooling means to the requirements of differently sized containers, and control means accessible externally of said casing to operate said 55 adjustable container guide means and spray means.

11. In a device of the character described, the combination with a frame, of a casing fixed to said frame, means on said frame for feeding containers along a predetermined path, spray means in said path for directing a cooling medium against the exterior of the containers, a refrigerating coil disposed in said casing beneath the path of container travel, cooling medium collecting means interposed between said path of container travel and said refrigerating coil, there being cooling medium discharge means in the bottom of said collecting means to direct the cooling medium over said refrigerating coil, and 70 75

means in said casing beneath said refrigerating coil to collect the cooling medium therefrom.

12. In a device of the character described, the combination with a frame, of a casing fixed to 5 said frame, means on said frame for feeding containers along a predetermined path, spray means in said path for directing a cooling medium against the exterior of the containers, a refrigerating coil disposed in said casing beneath the 10 path of container travel, cooling medium collecting means interposed between said path of container travel and said refrigerating coil, there being cooling medium discharge means in the bottom of said collecting means to direct the cooling medium over said refrigerating coil, means 15 in said casing beneath said refrigerating coil to collect the cooling medium therefrom, and pump means for circulating the cooling medium from said last named cooling medium collecting means 20 through said spray means.

13. In a device of the character described, the combination with a frame, of a casing fixed to said frame, means on said frame for feeding containers along a predetermined path, spray means 25 in said path for directing a cooling medium against the exterior of the containers, a hood disposed over said spray means, a refrigerating coil disposed in said casing beneath the path of container travel, cooling medium collecting means 30 interposed between said path of container travel and said refrigerating coil, there being cooling medium discharge means in the bottom of said collecting means to direct the cooling medium over said refrigerating coil, and means in said 35 casing beneath said refrigerating coil to collect the cooling medium therefrom.

14. In a device of the character described, the combination with a frame, of a casing fixed to said frame, means on said frame for feeding containers along a predetermined path, spray means 40 in said path for directing a cooling medium against the exterior of the containers, a hood disposed over said spray means, spray deflectors mounted in said path to normally engage the 45 containers beneath the open mouth thereof, a refrigerating coil disposed in said casing beneath the path of container travel, cooling medium collecting means interposed between said path of

5 container travel and said refrigerating coil, there being cooling medium discharge means in the bottom of said collecting means to direct the cooling medium over said refrigerating coil, and means in said casing beneath said refrigerating 10 coil to collect the cooling medium therefrom.

15. In a device of the character described, the combination with a frame, of a casing fixed to said frame, means on said frame for feeding containers along a predetermined path, spray means 15 in said path for directing a cooling medium against the exterior of the containers, a hood disposed over said spray means, adjustable spray deflectors pivotally mounted in said path to normally engage the containers beneath the open 20 mouth thereof, a refrigerating coil disposed in said casing beneath the path of container travel, cooling medium collecting means interposed between said path of container travel and said refrigerating coil, there being cooling medium discharge means in the bottom of said collecting 25 means to direct the cooling medium over said refrigerating coil, and means in said casing beneath said refrigerating coil to collect the cooling medium therefrom.

16. In a device of the character described, the combination with a frame, of a casing fixed to said frame, means on said frame for feeding containers along a predetermined path, adjustable 30 guide means in said path to direct the containers responsive to said feeding means, spray means in said path for directing a cooling medium against the exterior of the containers, a hood disposed over said spray means, adjustable spray deflectors pivotally mounted in said path to normally engage the containers beneath the open 35 mouth thereof, a refrigerating coil disposed in said casing beneath the path of container travel, cooling medium collecting means interposed between said path of container travel and said refrigerating coil, there being cooling medium discharge means in the bottom of said collecting 40 means to direct the cooling medium over said refrigerating coil, and means in said casing beneath said refrigerating coil to collect the cooling medium 45 therefrom.

WALTER C. HILGER.
